A METHOD OF MANUFACTURE OF BUFFING DISKS AND BONNETS

Ralph A. Salick, Brookfield, Wis.

Application April 12, 1954, Serial No. 422,306

6 Claims. (Cl. 300—21)

This invention relates generally to buffing pads or disks and to the manufacture of the same.

A general object of the invention is to provide an improved polishing or buffing disk or bonnet.

Another object of the invention is to provide a unique and novel manner of manufacturing buffing disks.

Another object of the invention is to provide a method of manufacturing buffing disks from a single and continuous strand of yarn, thread, fiber, ribbon, and the like.

Still another object of the invention is to provide a buffing disk in which all of the individual strands are simultaneously secured to a backing sheet and uniformly retained thereon.

Yet another object of the instant invention is to provide a method of manufacturing buffing disks wherein a continuous strand is uniformly wound on a form or core, secured together, and severed to provide a disk having a multiplicity of strands of uniform density and length.

Another object is to provide an improved pad comprised of a multiplicity of strands wherein each strand is individually secured in the pad structure and retained independently of each of the other strands therein to insure continued retention of all strands under severe commercial usage.

A further object of the invention is to disclose a method of manufacturing pads and the like utilizing a multiplicity of strands or fibers, in which a form or core having as a characteristic selective shaping and sizing, is used to manufacture pads of various shapes, sizes, and materials.

Another object of the invention is to provide a method of buffing disk manufacture in which a form or the like is used in a manner to receive a continuous strand of yarn, thread, wire, fiber, ribbon, or the like, and whereon the winding of the strand on the form may be readily varied to selectively alter the density of the pile and thereby obtain a finished product specifically designed for a desired purpose.

According to the invention, an improved buffing disk is provided, together with the disclosure of a new and novel method of manufacturing the same. Heretofore, polishing or buffing disks have been made by sewing together a multiplicity of weft strands in long strips and winding such strips to form a disk whereupon one face is coated with an adhesive and secured to a backing material. Obviously, this method requires a number of steps which are each time-consuming. The method proposed herein serves to utilize a flexible or rigid form or core upon which a single and continuous strand of yarn, thread, fiber, wire, ribbon, or any combination thereof, is rapidly wound, with the density of the strands in the disk being predeterminedly controlled by the compactness of the winding of the strand on the form strip. The width of the form strip used in the manufacture of the pads also serves to control the depth of the pile or strands in the pads or disks. After the core or form is thus completely wound, it is compressively formed to a predetermined shape, generally round or oval, and one edge face

2

is adhesively coated and secured to a backing material, such as canvas, cloth, or the like; after the adhesive has set, the form is readily removed in one of several ways and the buffing disk or pad is ready for commercial use.

5 Any pad or disk may be economically manufactured in the aforesaid manner with a minimum of waste.

The foregoing and other objects of the invention which will become more fully apparent from the following detailed description exemplifying the same, may be

10 achieved by the apparatus described herein in connection with the accompanying drawing, in which:

Figure 1 is a perspective view of a buffing disk operatively mounted on a power driven shaft, with said disk manufactured according to the inventive method dis-

closed;

Figure 2 is a detailed view of a portion of a flexible core strip with the continuous strand wound thereon;

Figure 3 is a detailed view of a buffing disk showing various detailed structure or make-up thereof;

20 Figure 4 is an enlarged detailed cross-sectional view of the buffing disk with the core still retained in the formed position;

Figure 5 is an enlarged detailed view similar to Fig. 4 showing the edges of the core strip pointed and with a

25 cutting plate positioned in a manner to simultaneously sever each of the weft strands to a uniform length; and

Figure 6 depicts a suggested manner for coiling the form strip adjacent a supporting wheel, which is power-driven; when the form is properly coiled to a predetermined diameter, the succeeding step in the manufacture of the disk may be performed.

30 Polishing or buffing disks, bonnets, or pads, are generally manufactured in any one of several ways. Originally such items were made by mounting a circular disk

35 of lambs wool on a backing plate; later, such items were made by sewing or adhesively securing long strips of weft strands onto a backing plate. The latter method provided a means for more properly securing the weft in the disks, so that the disks could be used commercially

40 under more rugged operating conditions wherein they could be rotated at considerably higher speeds. However, the continued demands of industry required that buffing disks be designed to operate at higher and higher speeds and under still more severe operating conditions. Especially in automotive and furniture plants, the need for a yet more rugged polishing disk is imperative. In such plants, literally thousands of such disks are completely worn out every day and need to be replaced at frequent intervals.

45 Referring more particularly to the drawing, and specifically to Fig. 1 thereof, a new and novel buffing disk 10 incorporating the particular features of the invention disclosed herein is shown operatively mounted on the end of a power driven flexible shaft 11. Such disks may generally be rotated at any of a plurality of speeds in the high or low speed range dependent mainly on the nature of the buffing work at hand. Since the inventive features of the buffing disk 10 exist primarily in the novel manner or method in which the disk is manufactured, the method 50 will be described in detail.

55 Ordinarily, polishing disks or pads are made in any of a number of ways including the use of a woven material such as carpet, circular disks of lambs wool, manufactured disks comprised of long strips of sewed weft strips secured to a circular backing disk, and others; while disks manufactured in the latter manner have one or more advantages over the others, they likewise have at least several inherent disadvantages or defects which greatly affect the desirability of using such disks commercially. Among these defects are lack of strength especially at higher speeds, not readily adaptable to economical production, and inability to be adapted to a

sufficiently wide range of commercial uses because of a lack of flexibility, length of nap or pile, and density.

The method of manufacturing polishing disks, as disclosed herein, serves to overcome each of these deficiencies, since the disks can be inexpensively made in a manner to provide means for readily controlling the essential factors, such as size and shape, depth of pile, degree of flexibility, degree of density, etc., and whereby the disks can be selectively manufactured of any one of a wide variety of materials with equal ease and facility. Included among the materials from which disks, bonnets, or pads can be made in the hereinafter described manner are wool, cotton, linen, fleece, silk, rayon, plastic or artificial yarns, jute, hemp, string, and wire. Generally, the less expensive textile materials are used for polishing and buffing pads or disks, although the more expensive materials may be used if the particular application warrants the use of the same. To obtain an extremely close and finely textured polishing pad, it is possible to utilize material known in the textile trade as "roving." Such material represents an intermediate step in the processing of textiles, i. e., after cotton or wool is carded, but prior to its being woven into strands. The "roving" comprises a plurality of extremely fine filaments that have been twisted slightly after carding. A polishing pad manufactured from "roving," and according to the teachings of this invention, provides such a fine and closely textured nap as to simulate a pad made of sheepskin.

The multiplicity of textile polishing or weft strands which go to make up the main body of the disk 10 in the instant method of manufacture originates from a single endless strand or coil 12 of the desired material. The word weft, as used throughout this application, is not used in its strict technical sense since no transversely extending warp strands are shown or required. For want of a more suitable or descriptive expression, however, the term weft is applied to those polishing strands adhesively secured together at their lower looped ends, or bonded at their looped ends, to a transversely extending backing member. The strand material is mechanically or manually wound clockwise or counter-clockwise around the edges of a long flexible forming strip ribbon 13, as shown in Fig. 2, such as spring steel, spring bronze, plastic, cardboard, or other suitable material. It should be noted that the width of the strip, as indicated by the numeral 14 in Fig. 2, serves to determine the depth of the pile or length of the weft strands in the finished polishing disk. In specific applications, a pad or disk with extremely short, medium, or long strands, may be of utmost importance; the use of the herein described method permits the manufacturer to readily control this variable, since he need only use a forming strip 13 of the requisite width.

Likewise, the thickness of the forming strip 13 is instrumental in helping to determine the density of the weft strands for any given area on the face of the disk; if a thin strip is used, it only stands to reason that less area is consumed than if a strip of greater thickness were used. On the other hand, in certain cases it may be desirable to use a thin forming strip for manufacturing pads but to inject a filler to control the density of the weft. Preferably, to provide the utmost density of the pile or nap, the forming strip or ribbon 13 is thinner in thickness than the diameter of the individual polishing strands, as shown in the drawings. Another means for controlling the density of the weft strands is by the degree of compactness with which they are wound around the forming strip 13. For example, if the endless strand is wound on the strip under extremely taut but uniform loads, a greater number of adjacent weft strands will be created per unit length of the forming strip than would be the case if lesser tensile loads were placed on the strand during the winding operation. Spacing between adjacent windings of the strand would also serve to reduce the number of weft strands per unit length of forming strip. The various possibilities in this regard are clearly exemplified in Fig.

2 wherein the compactly wound strand of textile material 12 is shown near the right end of the strip while the less compactly wound and greater spaced adjacent weft strands are shown toward the left end of the strip. However in actual production the strip would be wound with the strand under a predetermined load and rate to insure a uniform number of weft strands per unit of area on the face of the polishing disk or pad.

The manner in which the endless strand 12 is wound on the forming strip 13 may be effected in any one of several well-known different ways, including one in which the forming strip is axially rotated at a predetermined rate while the strand is controllably fed therein under a uniform tensile load, and another whereby the mechanism 15 serves to mechanically spin the strand around the forming strip as the latter moves forward at a uniform rate of feed. In any case, it is imperative that the strand be wound or placed thereon evenly and under a constant load in order to insure uniform density throughout the entire face of the pad or disk.

The next step in manufacturing pads or disks according to the teachings of this invention is to coil or wind the forming strip 13 under tension onto a clutch-driven winding block 15 operatively keyed to the end of a shaft 16 20 rotatively driven by the power source or motor 17, as shown in Fig. 6; a supporting or backing plate 18 of a diameter substantially larger than the diameter of the pad or disk being formed is keyed directly to the shaft 16. After the entire strip 13 has been wound on the block 15, the coiled forming strip can be readily removed from the coiling device since the outer end of the strip 13 is securely anchored to prevent unwanted uncoiling. The inner end of the strip 13 is secured in a radial slot 19 formed in the block 15; endwise removal of the coiled forming strip 13 may be readily effected without having the inner end of the strip bind in the block slot 19. It should be noted that any width of forming strip may be readily coiled on the block 15 and removed therefrom with a minimum of effort and without disturbing the textile strands thereon. It should also be noted that the winding block 15 may be any basic shape such as round, oval, square, rectangular, or triangular, so that the forming strip 13 coiled thereon may be readily shaped to form polishing pads in any desired shape. Or, conceivably, two or more forming strips 13 could be simultaneously coiled on the winding block with different textile materials on each strip, or with materials of different colors to permit variation in the pattern of the weft strands on the face of a polishing disk or pad. It should be apparent that one skilled in the art could conceive of numerous other ways in which the strips 13 could be coiled or wound and which would effectively serve to accomplish the aforesaid step.

As shown in Fig. 4, portions of the strand loops presented by one edge or face of the coiled forming strip 13 are coated with an adhesive 20 having desired adhesive qualities for the particular material being used. The face may be dipped, sprayed, or brushed, to insure an even coat of adhesive thereon, and to insure that the adhesive will penetrate the material and flow in and around all indentations and openings whereby each and every exposed strand is fully imbedded. Thereafter, the adhesive 20 can be subjected to heat, cold, pressure, or other medium, to effectively set or cure the same and weld all of the weft strands into a single unitary structure; a vulcanizing process could conceivably be substituted in place of the adhesive with equal effectiveness. The adhesive when cured or set, will act as a backing member and will serve to determine the flexibility of the finished buffing or polishing disk, or flexibility may be controlled by the type of backing material or member 21 applied to the back face of the disk or pad before the adhesive has set or cured.

In order to remove the forming strip 13 after the adhesive has securely locked the wound weft strands

thereon together in a single structure, one of several methods may be utilized. One example thereof is shown in Fig. 5 wherein the forming strip 13 is sharpened to a knife edge 22 on one of its longitudinal edges, so that when the forming strip is coiled the entire top face is made up of a series of coiled knife edges which will serve to sever or separate the tops of the weft strands upon the application of pressure or a sudden impact such as the operation of an impact or cutting plate 23 in a well-known manner. Note that the severing operation also serves to part or cut each of the strands to a precise uniform length whereby a user of the pad or disk is sure that each weft strand therein simultaneously engages a surface being buffed or polished. If a pressure type of adhesive is used in the manufacture of the disk or pad, two manufacturing operations may be performed simultaneously as suggested in Fig. 5 wherein the application of continuous pressure to plate 23 will first force the looped strands uniformly into the adhesive coated backing member 21 and thereafter effect the severance of the strands on the top face of the coiled form.

Other means may be used for removing the coiled forming strip 13 after the pad 10 has been completed. Examples of such means might conceivably include the application of a flame or heat to the top face of the coiled strip to effectively burn or disintegrate the strands at the point indicated by the top edges of the strips. Another means would comprise the use of a power driven or manually operated knife, grinder, or crushing roller, which would serve to effect a parting of the strands. If the nature of the material was such that it would not be desirable to sever the strands or if looped wefts were desirable, the form could be easily pulled out by pulling on the outer end of the forming strip 13. In any case, the weft strands are all cut to a uniform length in order to insure effective commercial utilization of the finished polishing disk.

Although the aforescribed method for practicing the invention is directed to applications in which a flexible core is coiled, it should be understood that a solid core strip could be used in certain cases wherein the strips would be stacked adjacent to one another to effectively present a series of rows of strands in the manufactured pad. In this case the core opening in the pad resulting from the winding operation could be eliminated.

In accordance with the teachings of the present invention, a new and novel buffing or polishing disk is provided. As aforesigned, in disks and pads presently available the strands are first secured, woven, or sewed together to form a strip which, in turn, is secured or sewed to the backing material in convolutions. The need for first sewing or weaving the strands together to provide an endless strip is completely eliminated in the present instance. Rather, each of the weft strands are firmly embedded and retained in a substantial layer of adhesive such as "latex." A back view of a completed polishing disk 10 is detailedly shown in Fig. 3 after the forming strip has been removed. Thus, it should be evident that the individual strands constituting the rear or anchoring face are evenly and compactly spaced and cemented together and to the backing material 21 by means of the adhesive 20; a center opening 24 is cut or formed in the disk 10 to receive a mandrel or other power-driven shaft for rotating the disk at a predetermined speed and permit the same to be brought into buffing or polishing contact with the work such as the surface of an automobile, metals, furniture, ceramics, machinery, plastics, appliances, flooring, woodwork, or the like.

It should be apparent that a disk or pad manufactured in the aforescribed manner has inherent characteristics which are vastly superior to those of any heretofore known or commercially used. The main feature, of course, is the fact that each polishing strand is se-

cured in the adhesive in such a manner that it cannot be extracted or pulled therefrom; rather, under unusual operating conditions, the strand will tear or part at some intermediate point. Another characteristic is the fact that the density of the strands can actually be carefully controlled in two ways to provide disks or pads for a variety of different purposes; likewise, since the width of the forming strip determines the depth of the pile, the same can be readily varied by using strips of different widths. All of the aforesaid factors may be varied regardless of the type of strand material which may conceivably be used in manufacturing the disks. Neither is it necessary to introduce any spacing or stuffing strands adjacent the anchoring face of the disk in order to space the weft strands protruding to the polishing face of the disk, as is generally done when manufacturing disks or pads in the usual manner.

Thus, regardless of the type of material or the purpose of the disk or pad, it is possible to use the identical method of manufacture by merely adjusting one of the aforementioned factors to meet a particular requirement. In all cases, the flexibility of the pad may be controlled because of the unitary and flexible body or base portion thereof. One skilled in the art will also readily note that a pad or disk could be built in the ascribed manner but without the use of a backing material 21; in this case, it would be necessary to cure or dry the adhesive completely so that the adhesive could serve in place of the backing material. The resultant construction would create an entire pad with closely welded or secured strands and with all parts tenaciously bound into a single mass to provide an exceptionally tough pad member capable of withstanding all of the wear and tear which industry could conceivably subject the same to under any known usage.

Since the disks are of uniform construction throughout, it should be apparent that they are perfectly balanced to permit rotation at the very high speeds presently required for certain prescribed buffing or polishing operations. Even the peripheral edge portions are uniformly formed and secured to preclude any difficulty if the extreme rotating edge of the pad or disk is accidentally brought into contact with the work surface. Since the strands are compactly disposed, the edgewise strands tend to mushroom outwardly and around the edge of the disk to provide a uniformly curved surface in the peripheral area.

The method of polishing disk or pad construction, together with the novel features of the disk or pad per se, can be readily adapted to numerous other applications by one skilled in the art; it is understandable that the principles of the invention as herein set forth may be used in modified form and detail without departing from the spirit and scope of the invention as described in the subjoined claims. It should likewise be borne in mind that other items in which the herein disclosed method of manufacture could be readily utilized are wax pads, carpeting, shoe buffers, paint rollers, dusters, wash mitts, fabrics, brushes, and other such items in which a nap rather than a smooth surface is a requisite; undoubtedly many more could be conceivably named.

The principles of the invention having now been fully explained in connection with the foregoing description of illustrative embodying apparatus, the invention is hereby claimed as follows:

1. A method of manufacturing polishing disks which comprises winding a continuous strand contiguously around a flexible form strip, coiling said form strip, adhesively coating portions of said strand loops as presented by one face of said coiled strip to secure each convolution of said strand thereon to adjoining strand convolutions, constituting a backing material thereto, and cutting said convolutions on the other face of said coiled strip to release said strip and provide a polishing disk having strands of a uniform pile length throughout,

2. A method of manufacturing a polishing pad that comprises winding a continuous polishing strand about a thin forming ribbon in a single layer of contiguous coils, coiling said forming ribbon with said polishing strand wound thereabout, applying the portions of said strand loops presented by one edge of said forming ribbon into engagement with an adhesively coated backing member, and applying sufficient pressure to the portions of the strand loops presented by the opposite edge of said forming ribbon to sever the portions of the strand loops to which pressure is applied and to embed the other portions of the strand loops into engagement with the adhesively coated backing member.

3. The method of manufacturing a polishing disk that comprises winding a strand about a flexible forming strip in a series of contiguous helical loops engaging said strip, coiling said forming strip with said strand wound thereabout in spiral shape, applying an adhesive to the outer portions of the strand loops presented by one face of said coiled forming strip, applying a plate member under pressure to the plurality of strand loops presented by the opposite face of said coiled forming strip in a manner to sever that portion of the strand loops between the face of said forming strip and said plate member, and removing said forming strip to produce a polishing disk comprising a plurality of folded strand loops adhesively secured together and a pair of strand portions respectively extending from the loops.

4. The method of manufacturing a polishing disk that comprises winding a continuous strand about a forming strip in a manner to form a single layer of elongated helical strand loops engaging the opposite side faces and opposite edges of said forming strip, convolving said forming strip with said strand loops thereabout in spiral form, applying sufficient longitudinal tension to said forming strip as it is wound in spiral form to place the portions of said strand loops between the opposite side faces of said forming strip under tightly packed radial compression, applying a layer of adhesive to the plurality of closely spaced strand loops presented by one edge of said forming strip wound in spiral form, and severing the portions of the strand loops presented by

the opposite edge of said forming strip whereby said forming strip may be removed.

5. The method of manufacturing a polishing disk that comprises winding a continuous polishing strand around a flat metal forming ribbon having one dull edge and one sharp edge in a manner that said strand is formed thereabout in a single layer of contiguous loops, coiling said metal ribbon with the continuous strand wound thereabout in a manner that the strand loops presented by the dull edge of said metal ribbon are adjacently disposed, applying a layer of adhesive on said strand loops, applying a backing member to the said layer of adhesive for securing each of said strand loops to said backing member, applying pressure to the portions of the strand loops presented by the sharp edge of said metal ribbon with sufficient force that said strand loops are severed by the sharp edge of said ribbon, and removing said metal forming ribbon.

20 6. A method of securing separate strands to a backing member that comprises winding a continuous strand about a flexible ribbon that is thinner in thickness than the diameter of said strand to form said continuous strand in a single layer of contiguous loops about said ribbon, coiling said ribbon supporting the contiguous strand loops, applying a thin layer of adhesive to that portion of the strand loops presented by one edge of said ribbon, bonding a backing member to the adhesively coated portions of the strand loops, and severing the portions of the strand loops presented by the opposite edge 25 of said ribbon to permit complete removal thereof and provide a unitary article thereby.
